CLAIM

The ornamental design for a positive plate for copper foil manufacturing equipment as shown and described.

DESCRIPTION

FIG. 1 is a perspective view of a positive plate for copper foil manufacturing equipment showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof, wherein the circles in FIG. 6 and the circles in FIG. 7 are through-holes connected to each other, and wherein the broken lines form no part of the claimed design.

1 Claim, 4 Drawing Sheets
